FLOAT SWITCH

Ted R. Wilson, Seattle, Wash., assignor to Boeing
Airplane Company, Seattle, Wash., a corpora-
tion of Delaware

Application May 17, 1952, Serial No. 288,499

3 Claims. (Cl. 200—84)

1

This invention relates to float actuated switches and more particularly concerns a control switch incorporating a rotatable magnet moved, by motion of a float, along an arc complementary to a curved soft iron armature which is concentrically mounted on a pivot to actuate movable elements that open and close electrical contacts.

The purpose of the invention is to provide a sensitive and positive operating switch which can be utilized for the critical control of fuel valve mechanisms installed in airplanes.

An object of the invention is to maintain the magnet at a substantially uniform level avoiding gravitational effects as much as possible.

A further object of the invention is to maintain relatively constant the distance between the magnet and the armature avoiding changes in magnetic attraction as much as possible.

The purpose and objects of the invention will become more apparent as the following description is read in conjunction with the accompanying drawings wherein like numerals designate the same part throughout the views.

Figure 1 is a sectional view through a portion of a float chamber containing the magnetic float switch mechanism.

Figure 2 is a partial-section perspective view.

More particularly, the invention comprises a float chamber 10 with rods 12 to receive guides 14 for controlling movement of a float 13, a connecting linkage 15 composed of a connecting rod fastened to the float 13 and pivotally connected to a crank arm 17 by pin 18 for transmitting float movement to the magnet 19 mounted above it on the shaft 20 between bearing supports 21, a curved soft iron armature 22 pivotally supported concentric with the arc of travel of the rotatable magnet 19 on the pin 23 held by the bearings 24 integral with the top 25 of the float chamber 10, and an electrical switch 26, mounted on the bracket 27 with an actuating plunger 28 located immediately adjacent the end 29 of the armature 22, for the control of electrical power distributed through the terminals 31, 32, 33, and utilized to operate valves (not shown) of a fueling system (not shown).

In operation the float 13 rises with the rising level of liquid in the chamber 10 interconnected with a fuel tank (not shown). The reciprocal motion of the float 13 is converted to rotary motion of the magnet 19 by the linkage 15. The swinging magnet 19 causes the armature 22 to pivot about the pin 23 until its end 29 contacts the plunger 28 of the switch 26.

Figure 1 illustrates the cooperating arrange-

2

ment of the parts in this contact position wherein the armature end 29 is pulled by the magnet 19 tipping the opposite end 29 against the switch plunger 28.

Lowering of the liquid level reverses the movements placing the magnet 19 opposite the armature end 29, releasing the plunger 28.

The valves (not shown) are either motor operated or solenoid operated and the motor or solenoid is energized by the closing of the float actuated switch.

For safety measures additional similar switch assemblies can be installed in the float chamber 10 to actuate other means to cut off the fuel supply if one assembly fails.

The electrical contacts within the switch 26 can be arranged similarly to the standard single pole, double throw switches employing an actuating pin or plunger, or some equivalent of the plunger could be employed such as an insulated mounting of a spring supported contact and terminal member on the curved armature to open one circuit and close another upon the rotation of the armature.

When necessary, in addition to improving the sensitiveness of the assembly by the suggested modifications of standard switches, the swinging magnet 19 could be counter-weighted neutralizing gravitational effects.

The inventive float switch as shown and described meets the requirements of a dependable and sensitive mechanism. The novel assembly maintains a relatively constant space between the swinging magnet 19 and the armature 22 without materially altering the vertical position of the magnet 19. This results in an ease of operation for the magnet moves comparatively free from changes in gravitational and magnetic forces.

The curved-path design as described and illustrated is the practical assembly of the more ideal horizontal-path design which reaches the ultimate in avoiding gravitational effects but presents the additional problems of reliably moving the magnet along a level path.

Having now particularly described and ascertained the nature of my said invention, and in what manner the same is to be performed, I declare that what I claim is:

1. A float actuated switch for control of electrical power for operating valve mechanisms comprising a float chamber, an arcuate non-magnetic top on the float chamber guide rods in the said float chamber, a float equipped with guide members and movably retained within the said float chamber by the said rods, a magnet

pivotedly mounted in the top central portion of the said float chamber, a linkage composed of a crank arm and rod connecting the said float to the said magnet converting the reciprocating motion of the said float to rotary motion of the said magnet, a curved armature pivotedly mounted on the arcuate non-magnetic top of the said float chamber immediately above the said magnet and concentric to its path of motion, and a switch mounted on the top of the said chamber having an actuating member located just above the end of the said armature permitting the pivoting armature to contact the switch thereby controlling the distribution of electrical power to valve mechanisms.

2. A float switch for automatic control of electrical operated fuel valves comprising a float chamber, an arcuate non-magnetic top on the said float chamber, a float slidably retained in the said chamber, a magnet rotatably mounted in the said chamber, a linkage between the said float and said magnet for transmitting the motion of the said float to the said magnet, a curved armature concentrically and pivotedly mounted outside the said chamber on the arcuate non-magnetic top above the said magnet along its path of circular motion, and a switching means mounted on the said float chamber with its actuating member above and within the pivoting arc of the end of the said armature permitting contact of the armature when the float rises actuating an electrical valve control circuit.

3. A float actuated switch installation in a fluid chamber for the automatic control of electrical operated mechanisms that regulate the flow of fluids in a fluid system, comprising a float chamber, a float slidably retained within the chamber

for reciprocal motion as the fluid level changes, a magnet rotatable in a vertical plane mounted within the chamber with its poles formed to complement the arcuate path defined by the poles themselves during oscillation, a connecting linkage between the reciprocal float and the rotatable magnet converting the reciprocal motion of the float to the rotary motion of the magnet, a non-magnetic arcuate separator forming part of the fluid chamber immediately above the magnet to accommodate the rotatable poles, an arcuate armature mounted outside the float chamber on the separator closely spaced thereto and formed complementary to the curvature of both the separator and the path traversed by the magnetic poles, a switching means mounted on the float chamber, and electrical contacts on the switching means placed over one end of the arcuate armature within the deflecting arc of the armature whereby the movement of the said magnet as the float rises will cause a rotary motion of the armature resulting in the closing of the electrical contacts and the actuation of electrical operated mechanisms that regulate the flow of fluids in the system.

TED R. WILSON.
